FIG. 4

FIG. 5

Fig. 1 is a front elevation of a helicopter showing my new design;

Fig. 2 is side elevation thereof;

Fig. 3 is a top plan view thereof;

Fig. 4 is a rear perspective view of the helicopter; and

Fig. 5 is a front perspective view thereof taken from the side opposite that shown in Fig. 4.

The dominant features of the design reside in the portions shown in full line.

I claim:

The ornamental design for a helicopter, as shown and described.
